SAFETY BAR FOR CYCLES

Robert C. Persons, 72 Commercial St.,
Worcester, Mass. 01608

Filed Feb. 19, 1968, Ser. No. 10,637

Term of patent 14 years

(Cl. D90—1)

FIG. 2

FIG. 1

FIG. 1 is a view in side elevation of a safety bar for cycles showing my new design, and

FIG. 2 is a view in front elevation looking in the direction of arrow 2.

The seat and tire shown in broken lines are included for illustrative purposes only.

I claim:

The ornamental design for a safety bar for cycles, as shown and described.
